UNITED STATES PATENT OFFICE

SAMUEL I. BOUSMAN, OF DENVER, COLORADO, ASSIGNOR TO THE DORR COMPANY, OF NEW YORK, N. Y., A CORPORATION OF DELAWARE

CONTINUOUS SETTLING APPARATUS

Application filed March 29, 1928. Serial No. 265,793.

This invention pertains to apparatus for sweeping non-circular areas with a continuous rotary movement, and is especially adapted for use in sedimentation apparatus such as clarifiers where settled solids are swept to a point of discharge. It is frequently desirable to employ clarifier tanks differing from the old round shape, rectangular tanks being usually preferred; but the removal of solids from the corners of such tanks, especially where the solids are heavy as in metallurgical operations, presents a difficult problem. Drag scrapers are subject to excessive wear and the submerged bearings are a constant source of trouble; while rotary mechanisms heretofore successfully used in practice are of the articulated type which with some materials requires periodical replacement of the submerged wearing parts necessarily employed.

The general object of this invention is to provide sweeping mechanism for the purpose indicated which is entirely free from submerged wearing surfaces or bearings, and is adapted to move heavy solids continuously to a point of discharge. Furthermore, the preferred arrangement is suitable for practical construction in the larger sizes sometimes required in sedimentation operations, clarifiers of two hundred feet in diameter being now in operation.

It is likewise, desirable, according to modern practice, to eliminate the bridge-like superstructures generally used for supporting the mechanism; and the present invention is adapted for support and drive without the use of a superstructure. It is also advantageous to employ peripheral drive on larger units, since for efficient sedimentation the linear speed of the outer end of the sweeping arm must not exceed a predetermined rate, as higher speeds will produce agitation which will disturb sedimentation. It is extremely difficult to provide the proper peripheral speed with a central drive in clarifiers of large size; while peripheral drive with a non-round clarifier tank has heretofore been considered impractical. This problem has been solved by the present invention, permitting the construction of rectangular clarifiers in

the large sizes employing peripheral drive. The arrangement however involves serious secondary problems, including the provision of a suitable central support, proper electrical connections which should extend from a center support to avoid the use of objectionable exposed contact lines around the periphery of the tank, additional raking capacity near the center of the clarifier, and adjustability to the inevitable irregularities in the supporting and guiding means around the periphery of the clarifier.

In general the present invention contemplates the use of a sweeping member supported and guided at one end by means extending around the periphery of the tank and which may follow a periphery of any desired contour. The other end of the sweeping member is supported in the interior of the tank, preferably at the center by means permitting both reciprocation and rotation; and for larger units the support should be a central pillar mounted in the clarifier. An independent central sweeping or raking device may also be rotatably mounted in the clarifier, and may be operated by the main sweep. This construction in turn involves many secondary problems of supporting and arranging the parts. The preferred embodiment of the invention is set forth in the following description taken in connection with the accompanying drawings, in which

Fig. 1 is a plan view of a sedimentation apparatus or clarifier embodying the invention;

Fig. 2 is a transverse vertical section on line 2—2 of Fig. 1, the sweeping or raking mechanism being shown in side elevation;

Fig. 3 is a detailed plan view of the peripheral drive unit, parts being broken away;

Fig. 4 is a vertical section on line 4—4 of Fig. 3 omitting the motor and showing the upper gear casing and worm pulley in elevation;

Fig. 5 is a plan view of the central supporting structure, parts being broken away; and

Fig. 6 is a section on line 6—6 of Fig. 5.

The clarifier 10 as shown is of a common type, including a substantially square sedimentation tank with slightly rounded corners. The feed enters through feed launder 100

11 and passes through inlets 12 into the clarifier. The supernatant liquid overflows into the launder 13 and passes out through discharge pipe 14.

5 The sweeping device, which in practice is usually referred to as a rake, includes a main reciprocating rake unit supported and guided at its outer end along the periphery of the clarifier, and supported and guided adjacent 10 its inner end at a point which preferably is at the center of the clarifier, by means which permits the unit to slide inwardly and outwardly in conformity with the movements of the outer end of the unit, while also permitting 15 the necessary rotary movement. Though a considerable variety of supporting structures for this purpose may be employed, the preferred form includes the use of a pillar 15 in approximately the center of the clarifier, with a suitable structure permitting both reciprocation and rotation of the rake 20 unit mounted on the upper end of the pillar. The latter also supports an auxiliary rake unit rotating with the main rake unit and 25 adapted to sweep the central portion of the clarifier. The solids are carried by these 30 units to a suitable discharge which should be located adjacent the center of the clarifier, and may conveniently include a gutter 16 about the base of the pillar 15, and an underflow discharge pipe 17 communicating with the bottom of the gutter.

The main rake unit comprises in general 35 a framework, raking means on the bottom thereof, supporting means on the inner end, and supporting and driving means on the outer end. The framework in the form illustrated comprises a truss 18 having spaced upper members 19 and spaced lower members 20, suitably interconnected and braced. Rakes 21 are mounted on its lower members 20, preferably comprising vertical blades set at an angle to the direction of travel of the truss 18 and positioned to sweep toward the center 40 solids which have settled on the clarifier bottom. These rakes may be constructed and arranged in accordance with standard practice, and may be of any known type, the invention not being restricted to the use of a 45 series of separate rakes. The rakes should extend along the bottom of truss 18 from a position adjacent the tank margin for a distance sufficient to provide suitable overlap with the auxiliary rakes during the entire 50 cycle of rotation.

The supporting and driving unit is shown 55 best in Figs. 3 and 4. The arrangement illustrated includes a framework carrying the end of the truss 18 and supported by roller 60 means on a suitable track 22 which passes around the periphery of the tank, and may be bridged over the feed inlets and the discharge for supernatant liquid. A self-contained electric motor drive unit is included, preferably 65 engaging the supporting roller or wheel;

and means also is provided for engaging the track 22 or other suitable structure for moving the truss 18 back and forth over the pillar 15.

The supporting frame includes a bed plate 70 75 23 on which the truss 18 is supported as by mounting the upper member 19 on opposite ends of the bed plate 23. An electric motor 24 is also mounted on the bed plate and is connected by belting 25 to pulley 26 on worm 27 which drives worm gear 28 whose vertical shaft 29 carries at its lower end a bevel gear 30 meshing with a bevel gear 31 suitably connected to a supporting and driving roller or wheel. An upper housing 32 mounted on the bed plate 23 encloses the worm 27 and worm gear 28 including suitable bearings for both, and preferably of the completely enclosed type adapted to be filled with a suitable lubricant. The bevel gear 30 projects from the lower part of the upper housing 32.

The supporting and guiding parts are mounted on a carriage 33 which should have pivotal movement relative to the bed plate 23. For this purpose the upper part of the carriage 33 includes a roller race 34 formed between suitable annular surfaces on the upper face of the carriage 33 and the lower face of the bed plate 23, in which a suitable series of rollers 35 mounted in rings 36 in the usual 95 manner is provided, the rotary movement being restricted to a fixed axis by a suitable means, such as the circular flange 37 on the bed plate 23 engaging a circular recess 38 in the carriage 33.

For obtaining adequate traction it is preferable to employ the supporting roller for traction purposes; and in the form shown this is conveniently accomplished by employing a roller 39 integral with the hub of gear 31 and having a wearing shoe 40 resting on the track 22. The roller 39, and of course the gear 31, are mounted on a shaft 41 carried in suitable bearings 42 in the carriage 33.

Means is also provided on carriage 33 for 110 resisting lateral movement as the carriage moves the adjacent end of the truss toward or from the pillar 15. This preferably comprises means such as rollers engaging opposite sides of the track 22, which may consist of standard railroad rails. In the construction shown guide rollers 43 are mounted in pairs on opposite sides of the track 22 at each end of the carriage 33, adapted to engage the sides of the track, the rollers of each pair being sufficiently spaced from the track to permit the necessary curvature of same when rounding the corners of the clarifier.

The construction for supporting and guiding the inner end of the main rake truss 18 and for supporting and rotating the auxiliary rakes, is shown in Figs. 5 and 6. In general, this arrangement includes a sliding support permitting reciprocation of the truss 18, a rotating support for said truss, a rotating 125 130

support for the auxiliary rakes, and an actuating connection between the auxiliary rake support and the parts rotated by the truss 18. In the construction shown a spider 44 is mounted on the upper end of pillar 15 and carries a circular track 45 on which is mounted the revolving head indicated generally at 46, which may include an outer frame ring 47 having an annular bearing flange 48 resting on the track 45, a suitable lubricant being provided between track 45 and the flange 48.

A supporting frame 75 for the truss 18 is pivotally mounted on opposite sides of the head 46, as by means of pivot shafts 49 extending through bearings in the frame ring 47 and mounted on the side members 50 which with the end members 51 form a rectangular supporting frame for the truss 18, the frame being of sufficient size to clear the head 46. The truss 18 is supported by the frame in suitable manner, as by means of rollers 52 carried by shafts 53 mounted in the frame.

A suitable track is provided in connection with the upper members 19 of the truss 18, for supporting the latter on the rollers 52. This track may consist of a channel 54 resting on each pair of aligned rollers and connected as by plates 55, angle 56 and plates 57 with the truss member 19. The rollers 52 have flanges 58 bearing against the inner faces of the channel tracks 54 to ensure rotation of the frame with the truss 18.

It is desirable to provide electric drive connections for the motor 24 from the pillar 15. While such connections may be accomplished in various ways, including the use of flexible wiring, a preferred arrangement is illustrated, which includes sliding contacts between fixed conductors on the pillar 15 and the rotating head 46, and sliding connections between conductors on the head 46 and conductors on the truss 18 which reciprocates relatively thereto. While a considerable variety of constructions may be employed, the form illustrated includes an inner frame ring 59 connected to the outer frame ring 47 by an annular top plate 60, the ring 59 preferably including also inner bearings for the pivot shaft 49. A series of bus rings 61 mounted on insulation 62 on the inner face of the frame ring 50 contact with a series of brushes 63 connected to wires passing downwardly through the cable 64 in the pillar 15, the brushes being mounted on an annular plate 65 resting on the spider 44 and extending from the inner part thereof to the outer frame ring 47, providing a lower closure for the space between said frame ring and the inner ring 59.

The bus rings 61 are connected through the flexible cable 66 to a corresponding series of brushes 67 mounted on a block of insulation 68 carried by a frame member 50 through angles 69, the brush connections preferably

being covered by a hood 70. The brushes 67 contact with a vertical series of bus bars 71 mounted on a block of insulation 72 carried by a channel 54. A suitable cable 73 running along a top member 19 of the truss 18 connects the bus bars 71 with the motor 24.

Auxiliary raking means may be provided for raking the central portion of the clarifier; both for the purpose of raking portions of the bottom not conveniently covered by the main rakes 21, and because of the substantially greater proportion of solids near the center of the clarifier, normally requiring additional raking to preserve the proper even travel of the solids to the central discharge. The auxiliary rakes may conveniently be supported from and actuated by the frame 75 or equivalent connections to the rotating head 46, which is automatically revolved by the truss 18. In the form shown four auxiliary rake arms are provided, including a long arm 74 extending in a direction generally opposite to that of the truss 18; a short arm 76 extending under the truss 18; and side arms 77 spaced between the arms 74 and 76. These arms are mounted on any suitable framework such as a rectangular bottom frame 78 to which the arms are directly attached; hangers 79 connecting the bottom frame 78 with the frame 75, preferably connecting with the end members 51 of the latter; and suitable bracing members 80 for the arms and the cage supporting same. Each auxiliary arm carries suitable sweeping or raking devices such as the rakes 21^a of the usual type adapted to impel solids into the discharge gutter 16; but obviously any suitable design or arrangement of rakes may be employed, and the invention is not limited to the use of a series of separate rakes, since other devices adapted by rotation to carry solids to the discharge gutter are known to those skilled in the art.

It is preferable in most cases to provide the raking zone of the auxiliary rakes with a slight slope toward the gutter 16, forming a central cone 81; and to employ a relatively flat surface 82 from the cone 81 to the periphery of the tank, over which the rakes 20 are operative. When this construction is employed the auxiliary rake 76 and the adjacent portions of the truss 18 are arranged so that the latter may slide in and out over said rake; but if desired all auxiliary rakes lying in the path of reciprocation of the rakes 21 may be dispensed with, in which case the use of a slope in the cone area 81 is optional, depending upon the material treated. It should be noted that while the cone 81 is shown as extending over a relatively small part of a clarifier area, this is for purely illustrative purposes, as it may be extended as far as desired toward the sides of the tank, the primary function of the truss 18 being to scrape the corners of the tank in a zone outside of a circle drawn from the axis of rota-

tion of the truss as a center with the distance to the nearest point on the side walls of the clarifier as a radius.

In operation the motor 24 is started by connecting the cable 64 with a suitable source of electricity (not shown) starting the motor 24 which through the intermediate gearing described rotates the roller 39, propelling the carriage 33 along the track 12. As the carriage 33 travels away from the pillar 15 it is held on the track 22 by rollers 43, pulling the truss 18 outwardly, the channel tracks 54 traveling over rollers 52 and rotating frame 75 and head 46 through engagement with the flanges 58 of said rollers. The auxiliary rakes 74, 76 and 77 are rotated over the cone 88 with the frame 75, while the rakes on truss 18 sweep the plane surface 82 continuously. As the carriage 33 approaches a corner guide rollers 43 cause carriage 33 to follow the track, the relative rotation between said carriage and the bed plate 23 being taken up by the bearing rollers 35; and rollers 43 engage the inner side of the track as the carriage 33 approaches the pillar 15, the truss 18 rolling inwardly on rollers 52. It is extremely difficult to lay the track 22 either in perfect alignment or in a true horizontal position; but it will be apparent that any defect in radial alignment is immaterial since the carriage 33 will follow a track of any contour and the truss 18 is free to move radially with the carriage; while minor variations in the level of the track are accommodated by the pivotal support of the frame 75 carrying the truss 18. Since the rollers 52 need not be positioned so that the rakes 21 will have reciprocating movement in a horizontal direction, the surface 82 likewise is not restricted to the horizontal; and it is well recognized that in certain fields of use a slope toward the center may be of value.

The clarifier operates in the usual way, with a steady gradual flow from feed to overflow, which in the form illustrated involves a flow across the entire tank from one side to another, although other arrangements of feed and overflow are well known and may be employed. The solids settling on the bottom are carried by the rakes 21 to the cone 81, and are then carried by the rakes 21^a to the discharge gutter 16, from which they flow through outlet pipe 17, being assisted if desired by scrapers 83 mounted on the auxiliary rake arms and extending into and across the gutter adjacent the walls thereof.

While this invention has been described as applied to a square tank for which it is primarily adapted, it will be apparent that it may also be fitted into tanks varying widely in contour, and that the mechanism may readily be installed in existing rectangular tanks whose dimensions do not vary too radically from the square. Furthermore, while the invention is primarily designed for sedi-

mentation purposes, for which purpose it is peculiarly adapted, certain features thereof may also be used in any apparatus in which a continuous sweeping movement over a non-round surface or zone may be required; and the apparatus itself is capable of actuation at a speed which may be utilized for stirring or other operations under proper conditions.

It should also be recognized that while peripheral drive and a central support from the bottom of the tank are both considered preferable, it is possible to dispense with either of these features under suitable conditions which will be apparent to those skilled in the art.

I claim:

1. Apparatus for sweeping a peripheral zone of a non-circular area including a sweeping member, means for guiding the outer end of the member along the periphery of the area, a support on which the inner end of the member is mounted by means permitting reciprocation of the member relative to the support, and means for driving the member.

2. Apparatus for raking a peripheral zone of the bottom of a non-circular sedimentation tank including a raking member, means for guiding the outer end of the member along the periphery of the tank, a support on which the inner end of the member is mounted by means permitting reciprocation of the member relative to the support, and means for driving the member.

3. Apparatus for raking a peripheral zone of the bottom of a non-circular sedimentation tank including a raking member, means for guiding the outer end of the member along the periphery of the tank, a support on which the inner end of the member is slidably mounted, and means for driving the member.

4. Apparatus for raking a peripheral zone of the bottom of a non-circular sedimentation tank including a raking member, means for guiding the outer end of the member along the periphery of the tank, a support, a rotatable element on the support on which the inner end of the member is slidably supported, and means for driving the member.

5. Apparatus for raking a peripheral zone of the bottom of a non-circular sedimentation tank including a raking member, means for guiding the outer end of the member along the periphery of the tank, a support, a rotatable element on the support on which the inner end of the raking member is slidably mounted, and driving connections between said member and element.

6. Apparatus for raking a peripheral zone of the bottom of a non-circular sedimentation tank including a raking member, means for guiding the outer end of the member along the periphery of the tank, a support, and a rotating element on the support including supporting means at opposite sides of the axis of rotation on which the inner end of said member is slidably supported.

7. Apparatus for raking a peripheral zone of the bottom of a non-circular sedimentation tank including a raking member, means for guiding the outer end of the member along the periphery of the tank, a support, a circular track on the support, and a frame rotatably mounted on the track and slidably supporting the inner end of the raking members. 5
8. Apparatus for raking the bottom of a non-circular sedimentation tank including a raking member, means for guiding the outer end of the member along the periphery of the tank, a support, a circular track on the support, a frame rotatably mounted on the track, 10 and sliding supporting bearings on opposite sides of the axis of rotation of the frame engaging the inner end of the member. 15
9. Apparatus for raking the bottom of a non-circular sedimentation tank including a raking member, means for guiding the outer end of the member along the periphery of the tank, a support, a rotatable element on the support, and roller bearings supporting the inner end of the raking member on said 20 element, said roller bearings being constructed and arranged to permit vertical movements of the inner end of the member corresponding to vertical movements of the outer end of said member during travel around the 25 periphery of the tank. 30
10. Apparatus for raking the bottom of a non-circular sedimentation tank including a raking member, means for guiding the outer end of the member along the periphery of the tank, a support, a revolving head mounted on the support for rotation about a fixed axis, supporting means movably mounted on the head, and means for slidably supporting the inner end of the member upon said supporting means. 35
11. Apparatus for raking the bottom of a non-circular sedimentation tank including a raking member, means for guiding the outer end of the member along the periphery of the tank, a support, a revolving head mounted on the support for rotation about a fixed axis, supporting means pivotally mounted on the head, and means for slidably supporting the inner end of the member upon said supporting 40 means. 50
12. Apparatus for raking the bottom of a non-circular sedimentation tank including a raking member, means for guiding the outer end of the member along the periphery of the tank, a support, a revolving head mounted on the support for rotation about a fixed axis, and supporting means pivotally mounted on the head at opposite sides thereof. 55
13. Apparatus for raking the bottom of non-circular tanks including a raking member, means for guiding the outer end of the member along the periphery of the tank, a central pedestal support in the tank extending above the liquid level, means for mounting the inner end of the member on said support above the liquid level permitting reciprocation of the member relative to the support, and means for driving the member. 60
14. Apparatus for raking the bottom of a non-circular sedimentation tank including a raking member, means for supporting the outer end of the member at the periphery of the tank, means for guiding the outer end of the member along the periphery of the tank, and means for supporting the inner end of the member within the periphery of the tank permitting reciprocation of said inner end, one of said supporting means including a single point of support transversely of said member, and the other supporting means comprising at least two points of support transversely of said member, the construction being such that a three point support arrangement is provided permitting said member to adjust its transverse position to the relative positions of the supports at all points during rotation of said member. 70 75 80 85
15. Apparatus for sweeping the bottom of non-circular sedimentation tanks including a raking member, means for guiding the outer end of the member along the periphery of the tank, a single roller supporting said outer end, a support for the inner end of the member, and means for supporting said inner end upon the support at two points spaced horizontally transversely of the member. 90 95
16. Apparatus for raking a peripheral zone of the bottom of a non-circular sedimentation tank including a raking member, means for guiding the outer end of the member along the periphery of the tank, a support on which the inner end of the member is mounted by means permitting reciprocation of the member relative to the support, and means at the outer end of said member for propelling said outer end along the periphery of the tank. 100 105
17. Apparatus for raking a peripheral zone of the bottom of a non-circular sedimentation tank including a raking member, means for guiding the outer end of the member along the periphery of the tank, a support on which the inner end of the member is mounted by means permitting reciprocating of the member relative to the support and electrical means at the outer end of said member for propelling said outer end along the periphery of the tank. 110 115
18. Apparatus for raking a peripheral zone of the bottom of a non-circular sedimentation tank including a raking member, means for guiding the outer end of the member along the periphery of the tank, a support on which the inner end of the member is mounted by means permitting reciprocation of the member relative to the support, electrical driving means at the outer end of said member for propelling said outer end along the periphery of the tank and electrical connections extending from said electrical driving means along said member and said support. 120 125 130

19. Apparatus for raking the bottom of a non-circular sedimentation tank including a raking member, a support, a rotating element on the support on which the inner end of the member is slidably supported, electrical driving means at the outer end of the member for propelling said end along the periphery of the tank, and electrical connections to said driving means extending along the member and including sliding connections mounted on the member and said rotating element.

20. Apparatus for raking the bottom of a non-circular sedimentation tank including a raking member, a support, a rotating element on the support on which the inner end of the member is slidably supported, electrical driving means at the outer end of the member for propelling said end along the periphery of the tank, and electrical connections to said driving means extending along the member and including sliding connections mounted on said rotating element and support.

21. Apparatus for raking the bottom of a non-circular sedimentation tank including a raking member, a support for the inner end of the member, a track extending around the periphery of the tank, means for supporting the outer end of the member, and means on said member engaging opposite faces of the track to guide the outer end of the member along the periphery of the tank.

22. Apparatus for raking the bottom of a non-circular sedimentation tank including a raking member, a support for the inner end of the member, a trackway extending around the periphery of the tank, a drive frame on the outer end of the member, drive means on the frame, a roller supporting said frame and traveling along the track, and gearing connections between the drive means and the roller.

23. Apparatus for raking the bottom of a non-circular sedimentation tank including a raking member, a support for the inner end of the member, a supporting roller for the outer end of the member traveling around the periphery of the tank, a carriage on which the roller is mounted, and a rotatable bearing supporting the outer end of said member on the carriage.

24. Apparatus for raking the bottom of a non-circular sedimentation tank including a raking member, a support for the inner end of the member, a supporting roller for the outer end of the member traveling around the periphery of the tank, a carriage on which the roller is mounted, a drive frame on the outer end of the member, drive means mounted thereon, a rotatable bearing supporting the drive frame on the carriage, and driving connections between the driving means and the roller.

25. Apparatus for raking the bottom of a

non-circular sedimentation tank including a raking member, a support for the inner end of the member, and means for supporting and driving the outer end of the member along the periphery of the tank including a supporting roller adapted to travel along the periphery, a carriage on which the roller is mounted, an annular roller bearing track on said carriage on which the outer end of the member is supported, and drive means on said outer end connected to the roller.

26. Apparatus for raking the bottom of a non-circular sedimentation tank including a raking member, a support for the inner end of the member and means for supporting and driving the outer end of the member including a roller adapted to travel along the periphery of the tank, a carriage on which said roller is mounted, a gear connected to said roller and carried by the carriage, a bearing on said carriage on which the outer end of the member is freely supported and drive gearing on said outer end engaging the gear on the carriage, the construction being such that said carriage and the outer end of the member are freely separable by relative vertical movement.

27. Apparatus for raking the bottom of a non-circular sedimentation tank including a raking member, a support for the inner end of the member, and means for supporting and guiding the outer end of the member along the periphery, a roller on the track, a carriage carrying said roller and mounted on the outer end of the member and a plurality of pairs of guide rollers mounted on the carriage and engaging opposite faces of the track, the adjacent faces of the rollers of each pair being spaced apart a distance sufficiently in excess of the transverse dimensions of the track adjacent the corners of the tank to compensate for the curvature of the track at such corners.

28. Apparatus for raking the bottom of a non-circular sedimentation tank including a raking member, means for supporting and guiding said member over the peripheral portions of the tank bottom and means for raking the central portion of the tank bottom.

29. Apparatus for raking the bottom of a non-circular sedimentation tank including a raking member, means for supporting and guiding said member over the peripheral portions of the tank bottom, means for raking the central portion of the tank bottom and driving connections between said member and the means for raking the central portion.

30. Apparatus for raking the bottom of a non-circular sedimentation tank including a raking member, means for guiding the outer end of the member along the periphery of the tank, a support, central raking means mounted on the support, and means for supporting the inner end of said member on the central raking means.

31. Apparatus for raking the bottom of a non-circular sedimentation tank including a raking member, means for guiding the outer end of the member along the periphery of the tank, a pedestal support on the bottom of the tank, central raking means rotatably mounted on said support above the water level, and means for slidably supporting the inner end of the raking member on said central raking means.

32. Apparatus for raking the bottom of a non-circular sedimentation tank including a raking member, means for guiding the outer end of the member along the periphery of the tank, a support, central raking means rotatably mounted on the support, means for slidably mounting the inner end of said member on the support, and driving connections between said inner end and said raking means.

33. Apparatus for raking the bottom of a non-circular sedimentation tank including a raking member, means for guiding the outer end of the member along the periphery of the tank, a support, a frame rotatably mounted on the support, means for slidably supporting the inner end of the member on the frame and raking means depending from the frame.

34. Apparatus for raking the bottom of a non-circular sedimentation tank including a raking member extending radially in said tank to the periphery thereof means for impelling said member along the periphery of the tank in a non-circular path to rake a peripheral zone in said tank, and central raking means raking the circular zone in said tank which includes the entire inner margin of said peripheral zone, the construction being such that the entire bottom of said tank is raked by said raking member and central raking means.

35. Apparatus for raking the bottom of a non-circular sedimentation tank including a raking member, means for impelling said member along a non-circular peripheral zone on the bottom of the tank and central raking means in said tank extending beneath the path of said raking member.

36. Sedimentation apparatus including a non-circular sedimentation tank having a bottom comprising a conical circular central portion and a flat peripheral portion extending from the central portion to the periphery of the tank; rotating raking means traveling over the central portion and rotating raking means traveling over the peripheral portion of the bottom.

In testimony whereof I affix my signature.
SAMUEL I. BOUSMAN.
